G. R. RICH.

TAPPET.

APPLICATION FILED SEPT. 18, 1916.

Patented Feb. 6, 1917.

Inventor:

George R. Rich,
by Charles O. Sherry,
his Atty.

UNITED STATES PATENT OFFICE.

GEORGE R. RICH, OF OAK PARK, ILLINOIS.

TAPPET.

1,215,062.

Specification of Letters Patent.

Patented Feb. 6, 1917.

Application filed September 18, 1916. Serial No. 120,740.

To all whom it may concern:

Be it known that I, GEORGE R. RICH, a citizen of the United States, and a resident of Oak Park, county of Cook, and State of Illinois, have invented certain new and useful Improvements in Tappets, of which the following is declared to be a full, clear, and exact description.

This invention relates to tappets of that kind adapted for use in connection with puppet valves of internal combustion engines.

It is well known to those skilled in the art to which this invention pertains that case-hardened valve tappets used in high speed motors are acted upon by the cams at extremely frequent intervals while the motor is running; moreover, that a strong, tough body is required and that the head portion or flange, which rides upon the cam, must be hard. In high speed motors the speed is so great that quite frequently the valve tappets are unable to follow the cams, because for one reason, the springs, which seat the valves and depress the tappets, do not act quickly enough to maintain continuous contact between the heads of the tappets and cams. Another reason may be the friction between the tappet and its bearing. The result is that after the cam has lifted the tappet to unseat the valve, and during the remainder of the greater portion of a cycle of its rotation, a gap is left between the cam and tappet head until the high part of the cam again reaches the head and strikes it a violent blow. The blows are usually struck approximately half way between the center and periphery of the head and often closer to the center.

The frequency of the blows and violence of the impact causes the skin or case-hardened surface portion to sink into the softer metal there-below, thus leaving indentations on the bearing face of the tappet head, and inasmuch as the tappet is free to turn in its bearing and does turn therein the bearing face of its head becomes indented, the indentation extending around the face of the head in the form of a ring or annulus. This deformation of the face of the tappet head is apt to seriously interfere with the proper timing of the motor, thereby decreasing its efficiency.

The primary object of this invention is to produce a tappet wherein the objectionable features above referred to are wholly

eliminated; furthermore, one of the objects is to provide a comparatively inexpensive tappet having such qualifications; furthermore, an object is to provide a one-piece tappet whose body or stem portion is strong, substantial and tough, and whose head is hardened throughout or substantially throughout. With these and other objects and advantages in view, this invention consists in a one-piece tappet whose head is hardened throughout while its body portion or stem is not hard throughout. The invention further consists of the several novel features hereinafter fully described and claimed.

The invention is clearly illustrated in the drawing accompanying this specification, in which—

Figure 1 is a side elevation of a tappet embodying a simple form of the present invention, a fragment of a cam shaft and a cam being shown in connection therewith;

Fig. 2 is a central, vertical section taken on line 2—2 of Fig. 1, and

Fig. 3 is a horizontal section taken on line 3—3 of Fig. 2.

Referring to said drawing, the reference numeral 4 designates a tappet embodying a simple form of my invention; 5, the cam shaft of an internal combustion engine, and 6, the cam on said shaft which acts on the head 7 of the tappet 4. It will be understood that in use the tappet is mounted in a bearing (not shown) formed in the engine, and that it lifts and unseats a puppet valve (not shown), which valve is seated by a spring and the tappet therewith depressed against or toward the cam. As previously mentioned, in high speed motors the cam 6 frequently rotates so rapidly that the tappet does not continuously contact with the cam, but a gap is left there-between after the tappet has been fully raised and until the high part of the cam again reaches it during the course of its rotation. Fig. 2 illustrates the parts in a position at the instant where the tappet and high part of the cam have come in contact, it being understood that prior to this instant the tappet was moving downward but out of contact with the cam, that the cam rotates in the direction of the arrow thereon, and that a gap has occurred between the head of the tappet and cam face which existed until the cam came in contact with it. The gap is shown between the face of the head and cam face

shown in dotted lines in Fig. 2; the width of said gap is somewhat exaggerated for the purposes of illustration. The ordinary tappets, made of case hardened steel and 5 acted upon in this manner, become ineffective in their operation because the cam indents the bearing face of the tappet head at the places where it strikes against it, since the skin or surface portion only is hard and 10 the underlying portions soft.

In the embodiment of my invention the tappet is constructed of light steel or a nickel alloy, or any alloy which may be case-hardened. As usual, the stem portion 8 is round 15 and bored out and tapped for the reception of the adjustment stem (not shown). On one end is formed the disk-like head 7, which is in the nature of a thin, disk-like flange extending out from the stem. After 20 the stem has been bored out part way I extend the bore down to within a short distance of the face 9 of the head by using a flat-ended or bottom drill so as to leave a flat or substantially flat face 10 at the bottom of the bore. The thickness of the wall 11, between 25 the faces 9, 10, should be such that when the tappet is subjected to the case hardening or carbonizing process the head will become hardened throughout. 30 Transverse openings 12 are formed in the wall of the stem 8, close to the head, which afford communication between the exterior of the stem and the interior of the bore adjacent the head, the purpose of which will 35 presently appear. Said openings may be formed by drilling in from the sides of the stem.

After the tappet has been formed as described, it is subjected to the case hardening 40 or carbonizing process, a clay core (not shown) being first inserted into the bore; the core should preferably extend down close to the openings 12, as indicated by the dotted line 13. It will be readily apparent that the 45 carbonizing material may enter the bore through the openings 12, so that not only is the outer surface portion of the tappet subjected to the hardening process, but the internal surface portion of the lower end of 50 the bored-out portion and faces of the openings 12 are subjected to such hardening process as well. The result is that the head portion is hardened throughout, or substantially

so, depending upon how thoroughly the hardening process is carried on, while the 55 stem portion is hardened on its surface portion only, the body of the stem remaining soft, tough and strong.

Inasmuch as the tappet head is hardened throughout, the danger of indenting the face 60 of the head is eliminated, making the tappet particularly efficient in a high speed motor.

More or less variation and alteration of the exact form of the invention shown and described is possible without departing from 65 the spirit of this invention. I desire, therefore, not to limit myself to the exact form set forth, but intend in the following claims to point out all of the invention disclosed herein. 70

I claim as new and desire to secure by Letters Patent:—

1. A tappet, comprising a case hardened single piece, consisting of a hollow stem portion formed with a head on one end, there 75 being openings through the stem portion adjacent the head whereby the head and adjacent stem portion may be case hardened on their outer and inner sides.

2. A tappet comprising a case-hardened 80 single piece, consisting of a stem portion and a disk-like head portion; there being openings through the stem portion adjacent the head for the admission of a carbonizing element. 85

3. A tappet comprising a single piece, consisting of a stem and a disk-like head on one end, there being a hollow space in the stem adjacent the disk, opening out through the wall of the stem, and the surface portion of 90 the head and surface portion of the hollow of the stem adjacent the head being case hardened.

4. A tappet comprising a single piece, consisting of a stem having a disk-like head on 95 one end, said stem having a bore extending therethrough terminating adjacent the head to thereby leave a thin wall between the face of the head and bore, and there being openings adjacent the head leading out from said 100 bore, the external surface portion of said stem and head and the internal surface portion of part of the stem, head and openings being hardened.

GEORGE R. RICH.
